UNITED STATES PATENT OFFICE.

WALTER J. NEWCOMB, OF EAST CLEVELAND, OHIO.

DESIGN FOR A FLAG, PENNANT, EMBLEM, OR ARTICLE OF A SIMILAR NATURE.

52,671.

Specification for Design.

Patented Nov. 12, 1918.

Application filed July 25, 1918. Serial No. 246,777. Term of patent 7 years.

To all whom it may concern:

Be it known that I, WALTER J. NEWCOMB, a citizen of the United States, residing at East Cleveland, in the county of Cuyahoga and State of Ohio, have invented a new, original, and ornamental Design for a Flag, Pennant, Emblem, or Article of a Similar Nature, of which the following is a specification, reference being had to the accompanying drawing, forming part thereof.

The figure is a plan view of a flag, showing my new design.

I claim:

The ornamental design for a flag, pennant, emblem, or article of a similar nature, as shown.

WALTER J. NEWCOMB.
